PROCESS OF DEWAXING PETROLEUM OILS
AND THE LIKEFredrik Teodor Emanuel Palmqvist, Stockholm,
Sweden, assignor to Aktiebolaget Separator-
Nobel, Stockholm, Sweden, a corporation of
Sweden

Application November 19, 1948, Serial No. 61,032

16 Claims. (Cl. 196—19)

1 This invention relates to the dewaxing of petroleum oils, shale oils, tars, and the like, and more particularly to an improved dewaxing process in which oil losses incident to removal of the wax are reduced.

Dewaxing is one of the most important steps in the production of lubricating oils, transformer oils, switch oils, etc., from petroleum oils, shale oils, tars or their fractions and residues. By removing such paraffinic hydrocarbons as precipitate at low temperature, the pour point and the cloud point of the oil is lowered so that it can be used for lubricating, insulating, chilling, etc., at low temperatures.

Low viscosity oils can easily be dewaxed by chilling to a temperature at which the paraffinic hydrocarbons precipitate in the form of solid crystals removable from the liquid hydrocarbons by filtration. Highly viscous oils, on the other hand, cannot be dewaxed in the same simple way but must be mixed with a suitable diluent or solvent in order to reduce the viscosity at low temperature and thus permit a satisfactory rate of separation of the wax. At the dewaxing temperature, the solvent should have a high solvent power for the oil and a low solvent power for the solid wax to be removed. With certain solvents and solvent mixtures, the difference in solvent power for oil and wax is so great that the solvents not only act as viscosity reducers but also as wax precipitators. Such solvents may be used to advantage for low viscosity oils as well.

Generally, the difference in solvent power for wax and oil increases with reduced temperature, and the higher the temperature at which this difference is noticeable, the higher is the temperature at which the dewaxing can take place. Since the economy of the dewaxing process depends mainly on the amount of chilling required, a solvent should be used which gives the smallest possible "spread," that is, the smallest possible difference between the dewaxing temperature and the desired pour point of the oil.

The solvent should also be chemically stable, easy to recover, non-corrosive and non-poisonous. Furthermore, it should be easily miscible with oil at low temperature, and the viscosity of the mixture should be low, so that uneconomically large quantities of solvent need not be used in order to render the wax easily separable by mechanical means.

The above-mentioned conditions are fulfilled by a great number of solvents widely used in the petroleum industry. Such solvents are, for instance, paraffinic hydrocarbons with low boiling point such as propane, hexane, light naphtha,

2 etc.; mixtures of ketones such as acetone or methyl ethyl ketone, with aromatic hydrocarbons such as benzol or toluol; chlorinated hydrocarbons such as ethylene dichloride per se or mixed with aromatic hydrocarbons such as benzol.

Generally the wax-bearing oil is mixed with the solvent at increased temperature, whereupon the solution is chilled to a temperature at which all or most of the wax is precipitated. The wax is then removed by settling, filtration or centrifuging, and the solvent is recovered from the oil and wax by distillation.

In this way, oil having the desired pour point is obtained and also a wax cake containing a certain amount of oil which not only represents a loss of valuable oil but also reduces the melting point of the wax and thus its sales value, the latter increasing in nearly geometrical progression with decreasing oil content and increasing melting point.

In order to improve the yield of dewaxed oil and the quality of the wax, the latter is generally deoiled further by being washed with the same solvent as used in the dewaxing process. When the wax is removed by filtration, this deoiling is often carried out by sprinkling the wax cake with fresh solvent; and when centrifugation is used to remove the wax, the latter is mixed with fresh solvent and centrifuged again. These methods have, however, the disadvantage that the quantity of solvent circulating through the system is considerably larger than the quantity of solvent required for the dewaxing only. The quantity of solvent used for deoiling the wax may be twice as great as the quantity of solvent required for removing the wax from the oil, particularly when treating oils rich in wax. Even if the economy of the deoiling can be improved by returning the washing liquid entirely or partially to the dewaxing process, where it is used as a solvent, the process involves a considerable complication since it must be carried out in at least two steps and requires an installation with a relatively large liquid volume, as well as accurate flow and temperature control of the liquids flowing partially in countercurrent and through heat exchangers.

The present invention has for its principal object the provision of a process by which the oil losses with the wax can be reduced in a simpler and cheaper way than described above. The process comprises essentially a centrifugation of the oil, in which precipitated wax is brought into contact with an auxiliary liquid having an interface tension in relation to the oil solution of less than 50 dyn./cm., thus displacing the oil solution

from the separated wax so that the latter is discharged from the separator bowl or centrifuging locus in a relatively oil-free state.

The process can be used to advantage for dewaxing by means of solvents having either a lower or a higher specific gravity than the wax to be removed, but in either case the auxiliary liquid has a specific gravity intermediate the specific gravities of the oil solution and the wax. In the first case, the auxiliary liquid must have a higher specific gravity than the oil solution, while in the latter case the auxiliary liquid should be lighter than the oil solution. In both cases, it is advisable to discharge the auxiliary liquid entirely or partially together with the wax.

Using the same quantity of solvent as otherwise required for the dewaxing step only, it is possible to obtain by this single-stage combined dewaxing and deoiling process a higher yield of dewaxed oil and a wax containing less oil, with considerably less consumption of power and steam for chilling and solvent recovery, than with the aforementioned prior methods. If, for example, an oil containing 25% wax is diluted with 200% by weight of light naphtha, followed by chilling to -28° C. and centrifuging without any auxiliary liquid, the yield is about 55% lubricating oil with a pour point of -15° C. and 45% wax with an oil content of about 45%. The same result is obtained by vacuum or pressure filtration. However, if the centrifugation is carried out in the presence of a suitable auxiliary liquid according to the invention, about 72% oil with a pour point of -15° C. and 28% wax with an oil content of only about 10% are obtained at the same rate of centrifugation. When filtering, or when centrifuging without any auxiliary liquid, at least two steps and 400% solvent would be required in order to obtain the same result.

The use of certain auxiliary liquids in connection with centrifugation has previously been proposed. In those prior cases, however, the auxiliary liquids are not of a character such that they are effective to displace oil from the wax separated in the centrifugal bowl. On the contrary, they act merely as carrier liquids; that is, they have such a high surface tension and specific gravity that the separated wax retains the occluded oil and is carried on the surface of the liquid in the same way as metal chips on mercury. As such carrier liquids, more or less concentrated solutions of inorganic salts in water, glycerine, etc., have been proposed.

The characteristics of the auxiliary liquid to be used according to this invention differ in principle in several respects from the so-called carrier liquids previously proposed, and should meet the following requirements:

1. The interface tension in relation to the oil solution should not exceed about 50 dyn./cm., so that the wax crystals can pass in contact with the auxiliary liquid as single particles and not as crystal agglomerates occluding large quantities of oil. Minor changes of the composition of the auxiliary liquid should not have any essential influence on the interface tension.

2. When using solvents with low specific gravity, the specific gravity of the auxiliary liquid should be equal to or higher than that of the oil solution and equal to or lower than that of the wax.

3. When using solvents with high specific gravity, the specific gravity of the auxiliary liquid should be equal to or lower than that of the oil

solution and equal to or higher than that of the wax.

4. The auxiliary liquid should be practically insoluble in the oil solution and easy to recover by heating, chilling, distillation, addition of inert substances, etc.

5. The auxiliary liquid should be miscible with water or other substances so that its physical properties can be adjusted according to the changes of the physical properties of the oil and the wax caused by variations of temperature, etc.

Examples of suitable auxiliary liquids are: aqueous ketones such as acetone, methyl ethyl ketone, diethyl ketone, etc., esters, nitro-, amino- or halogen-substituted aliphatic and aromatic substances, etc., especially those of typically polar nature, or mixtures of these substances, also with the addition of alcohols.

As previously mentioned, the dewaxing in the presence of an auxiliary liquid is preferably carried out by the action of centrifugal force. The wax-bearing oil is mixed with a suitable solvent and the wax is precipitated by chilling. If the specific gravity of the solvent is lower than that of the wax, the mixture is centrifuged in a cylindrical or conical centrifugal bowl at the periphery of which one or several wax discharge openings or nozzles are arranged. The auxiliary liquid is fed to the centrifugal bowl simultaneously with the waxy oil solution, preferably through a concentric inlet conducting the auxiliary liquid separately to the periphery of the bowl in order to avoid emulsification of the oil solution and the auxiliary liquid. Such a bowl is shown, for example, in British Patent No. 10,314 of 1908. The dewaxed oil solution is discharged through the central part of the centrifugal bowl, whereas the separated wax, together with the auxiliary liquid, leaves the bowl through the openings at the periphery.

From the dewaxed oil solution, the solvent is recovered in the conventional way by distillation. The wax is separated from the auxiliary liquid by means of heating, chilling, distillation, addition of precipitating agents, etc. Separation by means of heating involves special advantages, since the melted wax can be separated in liquid form from the auxiliary liquid. The heating can also be carried out in different steps, as in the usual wax sweating process, the waxes with low melting point being mixed in liquid state with the auxiliary liquid, whereas the waxes with high melting point are separated, as by the aid of centrifugal force. This procedure may also be carried out in reverse order, the mixture of auxiliary liquid and wax being heated to such a temperature that all of the wax is melted and the temperature then being gradually reduced, so that at first the hard waxes with high melting point are precipitated and separated, followed by precipitation and separation of the soft waxes with gradually decreasing melting point. The auxiliary liquid is finally returned to the process in a wax-free state.

When fractionating the wax in the presence of an auxiliary liquid, the latter's solvent power for certain oil components can be varied as desired by adding other auxiliary liquids, such as water, and, if desired, by changing the temperature at the same time. For this purpose, I prefer to use liquids which can be separated without difficulty from the main auxiliary liquid, for instance, by azeotropic distillation, etc., whereby a redistillation of the whole auxiliary liquid mixture can be avoided.

Sometimes it may be advisable to carry out the dewaxing or deoiling procedures, or both, in several steps. The wax concentrate from the first step is centrifuged in a second step, preferably after further addition of solvent, using auxiliary liquid in both steps. It is also possible to exclude the auxiliary liquid, for instance in the first step, and to mix the wax concentrate with auxiliary liquid before it is centrifuged in the next step. Under certain conditions it may be sufficient to feed the wax concentrate from the first step directly into the second centrifuge bowl together with the auxiliary liquid.

As compared with the prior multi-stage methods, the process of the present invention has the advantage that the solvent quantity is considerably smaller, generally less than 50% of the total solvent quantity required with ordinary methods, and that the "spread" is smaller because the separated wax when passing through the auxiliary liquid is no longer in contact with the oil solution, whereby the unavoidable slight temperature increase caused by the centrifugation does not impair the pour point of the oil as would otherwise be the case due to re-solution of wax.

The use of an auxiliary liquid for centrifugal separation of solid from liquid substances according to the invention may also be used to advantage in other chemical and industrial processes within or outside the petroleum field, particularly when the problem is to separate, in a technically pure form, solid or semi-solid substances which are difficult to filter, for instance organic or inorganic salts from viscous solutions, emulsions, etc.

In the accompanying drawing, the single illustration is a schematic view of an installation suitable for practicing the invention in the dewaxing of oils.

Wax-bearing oil and solvent are mixed in fixed proportions and the resulting solution is chilled to the desired dewaxing temperature in the cooler 1, after which the separation is effected in centrifuge 2.

The solvent is then recovered from the oil solution obtained in the separation, by distillation in the distilling apparatus 3, and is returned to the process. Wax-free oil with the desired pour point is obtained from apparatus 3 as distillation residue. During the centrifuging, auxiliary liquid is fed from cooler 1 to the separator 2, the bowl of which may be provided with nozzles at the periphery, the auxiliary liquid preferably being introduced at the periphery of the bowl in front of the nozzles, as previously described. Part of the wax-bearing auxiliary liquid discharging from the separator bowl may be returned to the separator, as shown at 2a, if the wax content is not too high. The remaining portion, after being heated in the heater 4, is mixed with water or some other additive which reduces the solubility of the wax in the auxiliary liquid at high temperature, the solubility reducer being added through pipe 8. The resulting two fluid phases are separated from one another in the separator 5, into an oil-poor wax containing small amounts of auxiliary liquid which may be driven off and returned to the system, and auxiliary liquid containing the added solubility reducer (for example, H_2O) and small amounts of oil and wax. After distilling the auxiliary liquid in the distillation apparatus 6, the solubility reducer may be returned to the system through pipe 8. The recovered auxiliary liquid is likewise returned, after cooling in the

cooler 7. Small amounts of a wax-containing oil are obtained as balance from the apparatus 6, and this balance may be subject to a repetition of the treatment to which the original wax-bearing oil is subjected.

The above procedure has been described only by way of example, and it will be understood that other embodiments are possible within the scope of the invention.

I claim:

1. In the dewaxing of mineral oils, shale oils, tar oils, and their fractions and residues, by centrifuging the oil in the presence of an added oil-dissolving and wax-precipitating solvent, said solvent forming with the oil an oil solution containing precipitated wax crystals, the process which comprises forming in the centrifuging locus, and adjacent the oil solution, a layer of an auxiliary liquid having a specific gravity intermediate the specific gravities of the oil solution and the wax, said auxiliary liquid being substantially insoluble in the oil solution and having a surface tension, relative to the oil solution, which is sufficiently low to allow the wax to pass into said layer in the form of separate crystals while preventing penetration of oil into said layer, and, during the centrifuging operation, passing wax crystals separately through the boundary surface between said oil solution and layer while displacing oil from the wax at said layer, thereby deoiling the wax in said locus.

2. The process according to claim 1, in which the specific gravity of the auxiliary liquid is higher than that of the oil solution but lower than that of the wax.

3. The process according to claim 1, in which the specific gravity of the auxiliary liquid is higher than that of the wax but lower than that of the oil solution.

4. The process according to claim 1, comprising also the step of adding water to the auxiliary liquid to adjust its interface tension to within the prescribed limit in relation to the oil solution, the auxiliary liquid being soluble in water.

5. The process according to claim 1, comprising also the step of adding water to the auxiliary liquid to adjust its specific gravity to an amount intermediate the specific gravities of the wax and the oil solution, the auxiliary liquid being soluble in water.

6. The process according to claim 1, comprising also the steps of continuously introducing the auxiliary liquid into the centrifuging locus, and continuously discharging said liquid with separated wax through the outer periphery of said locus.

7. The process according to claim 1, in which the auxiliary liquid is introduced into the centrifuging locus outside the interfacial zone between the separated wax and the separated oil solution in said locus.

8. The process according to claim 1, comprising also the steps of discharging from the centrifuging locus a mixture of auxiliary liquid and wax, and fractionating said mixture by thermal treatment to separate the wax from the remaining oil.

9. The process according to claim 1, comprising also the steps of discharging from the centrifuging locus a mixture of auxiliary liquid and wax, separating the wax and remaining oil from said mixture, and subjecting said last wax and oil to further treatment to recover the oil from the wax.

10. The process according to claim 1, comprising

ing also the steps of discharging from the centrifuging locus a mixture of auxiliary liquid and wax, adding a solubility reducer, in which the auxiliary liquid is soluble to said mixture to reduce the solubility of the wax in the liquid at high temperature, separating the mixture into a component mainly of wax and a second component mainly of auxiliary liquid and solubility reducer, distilling said last component to recover separately the auxiliary liquid and the solubility reducer, and returning said last liquid and reducer to the process.

11. The process of dewaxing petroleum oils, shale oils, tar oils, their fractions and residues, which comprises continuously feeding the wax-bearing oil and an oil solvent to a centrifuging locus and there separating the same into an oil solution and wax, contacting said wax, while in said locus, with an auxiliary liquid substantially insoluble in the oil solution and having an interfacial tension in relation to the oil solution of less than 50 dyn./cm., said liquid having a specific gravity intermediate the specific gravities of the wax and the oil solution, passing the wax through the boundary surface between the auxiliary liquid and the oil solution in said locus, whereby said liquid displaces oil entrained in the separated wax, and discharging the wax and auxiliary liquid from the locus separately from

the initially separated oil and said displaced oil.

12. The process according to claim 1, in which the auxiliary liquid is an aqueous ketone.

13. The process according to claim 1, in which the auxiliary liquid is an ester.

14. The process according to claim 1, in which the auxiliary liquid is a substituted aliphatic compound.

15. The process according to claim 1, in which the auxiliary liquid is a substituted aromatic compound.

16. The process according to claim 1, in which the auxiliary liquid includes alcohol.
